UNITED STATES PATENT OFFICE.

ARTHUR A. BRIGHAM, OF BROOKLINE, MASSACHUSETTS, ASSIGNOR TO WARREN H. BUTLER, TRUSTEE, OF DANVERS, MASSACHUSETTS.

CORD.

1,172,339.

Specification of Letters Patent. Patented Feb. 22, 1916.

Application filed December 27, 1913. Serial No. 809,123.

To all whom it may concern:

Be it known that I, ARTHUR A. BRIGHAM, a citizen of the United States, residing at Brookline, in the county of Norfolk and 5 Commonwealth of Massachusetts, have invented a new and useful Cord, of which the following is a specification.

My invention relates to braided cord.

As illustrative of my invention, I will 10 take window cord which is ordinarily made by braiding together a number of strands of fibrous material, such as jute, linen or cotton. Such cord may have great tensile strength, but in its use as window cord, the 15 constant strain and tension and the wear on the strands materially shorten the life of the cord.

In my new cord the strands which are 20 braided together consist of a core of fibrous material, such as jute, linen or cotton, covered with paper. Preferably all of the strands of my new cord should be paper covered, although a cord may be made wherein less than the whole number of 25 strands are paper covered and still be within my invention and have substantial advantages.

I believe that my new cord has substantial 30 advantages over cord as ordinarily made, the paper cover about the strands cushioning

the strands and resisting the chafing, one against the other, to which they are subjected, and adding materially to the life and strength of the cord.

The annexed drawing shows a piece of 35 braided cord, such as is ordinarily used for window cord, made in accordance with the preferred form of my invention, with each of the strands paper covered. Two of the strands are broken away showing the core 40 of fibrous material at *a* and the paper cover at *b*.

I claim as my invention:

1. A braided cord containing strands which consist of a core of fibrous material 45 covered with paper.

2. As a new article of manufacture a braided cord containing strands composed of a core of fibrous material such as jute, 50 linen or cotton, and provided with a cover of paper, which cushions the cores and prevents said cores from cutting.

In testimony whereof, I have signed my name to this specification in the presence of two subscribing witnesses.

ARTHUR A. BRIGHAM.
